(57) **CLAIM**

The ornamental design for a nasal cannula assembly, as shown and described.

DESCRIPTION

FIG. 1 is a perspective view of a nasal cannula assembly.

FIG. 2 is a rear view thereof.

FIG. 3 is a front view thereof.

FIG. 4 is a left side view thereof.

FIG. 5 is a right side view thereof.

FIG. 6 is a top view thereof; and,

FIG. 7 is a bottom view thereof.

A tube of the nasal cannula assembly is shown with a symbolic break in its length. The appearance of any portion of the article between the break lines forms no part of the claimed design.
